UNITED STATES PATENT OFFICE.

THOMAS H. MUSSELMAN, OF RICHMOND, TEXAS.

FOLDING TABLE.

Application filed March 21, 1922. Serial No. 545,512.

To all whom it may concern:

Be it known that I, THOMAS H. MUSSELMAN, a citizen of the United States of America, residing at Richmond, in the county of 5 Fort Bend and State of Texas, have invented new and useful Improvements in Folding Tables, of which the following is a specification.

In carrying out my present invention it is 10 my purpose to provide a folding table wherein the supporting members may be folded into the table top and the end sections folded against the under side of the main section to cover the supporting members 15 and present a neat and compact folded structure which may be readily carried about from place to place.

It is also my purpose to provide a folding table wherein the parts may be locked in 20 folded position and wherein by means of auxiliary sections the area of the table top may be increased and the formation of the table top changed to suit the exigencies of the user of the table.

25 My improved folding table will be found particularly useful by paper hangers, although it will be understood that it may be employed for a variety of purposes.

With the above recited objects in view, 30 and others of a like nature, the invention resides in the construction, combination and arrangements of parts set forth in and falling within the scope of the appended claims.

In the accompanying drawings:

35 Figure 1 is a side elevation of my improved table in open position.

Figure 2 is a longitudinal sectional view through the same, one end section being shown inactive.

40 Figures 3 and 4 are top plan views showing the auxiliary sections in different positions.

Figure 5 is a bottom plan view showing the supporting members folded into the 45 table top.

Figure 6 is a sectional view on the line 6—6 of Figure 3.

Figure 7 is a perspective view showing the table folded.

50 Figure 8 is a perspective view of a detail of the invention.

Referring now to the drawings in detail 1 designates a rectangular frame comprising side bars spaced apart in parallelism and 55 end bars connecting the side bars. The in-

ner edges of the side and end bars are rabbeted as at 2 at the upper edge of the frame and seated in the rabbeted portions is a top member or plate 3 of veneer or other thin material. Fastened to the under surface of 60 the plate 3 are reinforcing strips 4 appropriately spaced apart. The frame and plate constitute the main section or top of my improved folding table.

Connected to the respective end bars of 65 the main section are supporting sections each comprising legs 5—5 spaced apart in parallelism and connected together by a cross bar 6 arranged, in the present instance, adjacent to the floor ends of the legs and 70 upstanding brace bars 7 connected to the legs and cross bar. At its upper end each supporting member is connected to one of the end bars of the table top by means of 75 hinges 8 or other similar connecting devices, and in accordance with my invention the hinged end of one supporting member is connected to its end bar in a plane higher than the hinge connection between the other supporting member and end bar, so that 80 when the legs are folded against the under side of the table top and into the frame 1, one supporting member will lie close to the table top and the other overlap the first folded supporting member, so as to present 85 a neatly folded and compact arrangement of the parts as shown in Figure 5 of the drawings, the supporting members lying in parallelism with each other and with the table top.

Hinged as at 14 or otherwise pivotally connected to the ends of the main section are end sections 9 each comprising, in the present form of my invention a frame 10 of a width corresponding to that of the main section and of a length substantially equal to one-half of the length of the main section. The upper edges of the side and end bars of the frame 10 are rabbeted as at 11, and seated in the rabbeted portion is a plate 100 or top member 12 reinforced by a strip 13.

In order to hold the supporting members in table forming position I employ foldable brace bars 15 that connect the main section with the supporting members, as shown in 105 Figures 1 and 2. These brace bars are arranged in pairs and those of each pair connect with the respective side bars of the frame 1 as at 16 at their upper ends and with the respective legs 5 of the correspond- 110

ing supporting member at their lower ends, as at 17. These connections 16 and 17 are permanent pivotal connections.

Each foldable brace bar 15 comprises, in this form of my invention, two sections 18 and 19 having their outer ends pivotally connected with the table top and supporting member respectively and their inner ends overlapping as at 20 and pivotally connected to each other as at 21. The overlapping end of the section 18 is curved upwardly as at 22 and formed with a lip 23 that engages the upper edge of the companion section 19 as clearly shown in Figure 8, so that movement of the sections 18 and 19 to brace formation will be limited and the sections held in such formation as illustrated in Figures 1 and 2 of the drawings.

The end sections 9 are also held in table formation by braces 24 each identical in construction to the braces 15 heretofore described. These braces 24 are arranged in pairs and those of each pair are pivotally connected at their upper ends to the respective side bars of the corresponding end section 9 adjacent to the outer end of said section, while the lower ends of said braces are formed with depressions 25 respectively, as in Figure 8, to detachably engage pins 29 carried by the respective legs 5. For convenience in folding the table the brace bars 15 connect with the outer edges of the legs 5, while the brace bars 24 connect with the inner edges thereof as clearly depicted in Figures 1, 2 and 6 of the drawings.

To fold my improved table the joints formed by the overlapping ends of the brace bars 15 are broken and the legs or supporting members folded into the table top as previously described. The joints formed by the overlapping ends of the brace bars 24 are now broken and the end sections 9 folded against the under side of the main section to present a suitcase-like appearance as shown in Figure 7.

The main section of the table carries a handle 26 that extends through slots in the side bars of the main section whereby the folded structure may be conveniently carried. In the folding of the end sections 9 the lower ends of the brace bars 24 are disconnected from the pins 29 and the brace bars folded alongside the respective side bars of the end sections.

In order to lock the end sections and main section in folded position I employ a lock-

ing rod 30 having one end sliding in a keeper 31 carried by the under side of one of the sections 9 and the other end slidable 60 through a slot in one side bar of the section 9. Pivoted to the under side of the section 9 adjacent to the last named end of the rod 30 is a lever 32 having one end pivotally connected with the rod and the other end pivoted to a sliding bolt 33. The bolt 33 and the end of the rod 30 remote from the bolt cooperate with keepers 34 carried by the respective side bars of the main section, as shown in Figures 1 and 2 of the drawings, 70 and when engaged with said keepers lock the parts in folded position.

35—35 designate auxiliary sections whose combined lengths equal that of the main and end sections of the table, as shown in Figure 3. Each section 35 is equipped with transversely extending bars 36 that project beyond the side bars on one side of the sections and are suitably spaced apart and interchangeably engageable in sockets 37 formed in the side bars of the main and end sections of the table and sockets formed in the other side bar of the companion section, as shown in Figures 3 and 4.

While I have herein shown and described one preferred form of my invention by way of illustration, I wish it to be understood that I do not limit or confine myself to the precise details of construction herein shown and described, as modifications and variations may be made within the scope of the claims and without departing from the spirit of my invention.

Having thus described my invention, what I claim as new, is:—

In a folding table a main section comprising a rectangular frame having its inner side at the top edges rabbeted, a top member seated in said rabbeted edges and fastened therein, supporting sections hinged to the side bars of said frame respectively, the hinge connection between one supporting section and the corresponding side bar being in a higher plane than the similar connection of the remaining supporting frame so that the supporting sections may be swung into said frame and overlap each other in parallel relation, auxiliary sections, and means whereby said auxiliary sections may be interchangeably connected to each other and to said main and end sections.

In testimony whereof I affix my signature.

T. H. MUSSELMAN.
